UNITED STATES PATENT OFFICE.

CHARLES E. HAWKINS, OF CINCINNATI, OHIO.

METHOD OF REDUCING AND GRADING PULP.

Application filed April 27, 1921. Serial No. 464,941.

To all whom it may concern:

Be it known that I, CHARLES E. HAWKINS, a citizen of the United States, and residing at Cincinnati, in the county of Hamilton and State of Ohio, have invented a new and useful Improvement in Methods of Reducing and Grading Pulp, of which the following specification is a full disclosure.

This invention relates generally to the art 10 of paper-making and particularly to the process of reducing or disintegrating paper pulp to a graded product in a continuous operation.

The process, as herein described and 15 shown, is made applicable to a type of pulp reducing machine, known as a hollander or beating engine, into which the raw stock ungraded pulp or half stuff, from any source or of any material, is operated upon for a 20 finer reduction and grading preparatory to its transfer to the chests or to the bleaching tanks, to condition the pulp for subsequent use in the manufacture of paper or box boards.

25 In the methods now generally practiced, a beater tub is filled with raw stock ungraded pulp or half stock and the entire mass reduced to a proper degree of fineness and then dumped into a chest. Certain 30 methods for continuously grading pulp, however, are in use, such as a revolving screen or grader, which is partially immersed in the beater tub through which the reduced pulp passes, or the material is 35 allowed to pass over a stationary screen for discharging from the tub. In these methods, the screen readily clogs, reducing the capacity of the machine and causing interruption in the operation.

40 It is therefore an object of the invention to provide a method of grading and continuously discharging the graded pulp through a non-clogging, self-cleaning, revolving screen or grading drum disposed 45 adjacent to the beater or disintegrating roll, whereby the material as reduced is conveyed to and cast upon the non-clogging, revolving screen by the revolving beater or disintegrator for the immediate grading and dis- 50 charge from the tub.

Another object is to place the non-clogging revolving screen, composed of hinged bars or members, in close proximity or adjacent to the beater roll and rotate the same 55 in a direction opposite to the direction of beater rotation, whereby the coarse material

and such as will not pass through the screen mesh will be carried forwardly by the screen in an advancing direction, to prevent an accumulation between the beater roll and 60 screen, and to permit the conveyed material to be dropped from the descending side of the screen, either by gravity or action of the screen member.

Another object of the invention is to form 65 a revolving screen of hingedly mounted bars or elements, independently swinging to a vertically suspended open position at the descending side and return revolution or half-cycle of the roll, for releasing any adhering pulp material, cleaning the members and providing a full mesh opening after the members move to their closed position on the upward or forward half cycle.

Other objects and certain advantages will 75 be disclosed in the description of the drawings and reference is made to said drawings, in which:

Fig. 1 is a plan view of a hollander or beating machine, illustrating the application 80 of my invention thereto.

Fig. 2 is a side elevation, parts being broken away to disclose the inner structure and relations.

Fig. 3 is a longitudinal, vertical section on 85 line 3, 3, Fig. 4, illustrating the structure of my grading, straining and self-cleaning drum.

Fig. 4 is a vertical, transverse section on line 4, 4, Fig. 3.

Figs. 5, 6 and 7 are respectively an elevation, plan, and reverse plan, of one of the screen fingers of my drum.

Fig. 8 is a section on line 8, 8, Fig. 5.

Fig. 9 is a fragmentary view, similar to 95 Fig. 4, showing a modified form of screen finger.

Fig. 10 is a plan view of the modified finger structure, shown in Fig. 9.

Fig. 11 is an end view of the same.

Referring to the drawings, 1 indicates the tank or vat of the hollander, of the usual form, with a central partition 2 extending longitudinally of the tub, termed a "mid feather," dividing the interior of 105 the tub to an oval course for continuously traversing the pulp mass. About midway of one of the course runs, the bottom extends upwardly to form a transverse wall 3, curved on one side, conforming to the 110 curvature of the beater roll 5 and inclined on the reverse side toward the vat bottom.

The beater or disintegrator roll carries on its circumference a number of radially extended knives for cooperating with similar knives centrally beneath the roll, secured 5 into and extending from the bed plate 4. The beater roll is journaled upon the adjustable bearing, so that the distance between the two sets of knives may be regulated. The roll 5 is revolved in the direction shown by the arrow in Fig. 2, and the pulp is drawn in between the roll, knives and stationary knives, and between the roll and the curved bottom of the cross wall, and conveyed upwardly to be cast upon the grading roll.

The tub and construction of the pulp reducing mechanism is substantially of commercial design well known to the art to which no claim of novelty is made herein.

20 Mounted crosswise of the tank, behind the back fall and beater roll is my straining, grading and self-cleaning drum, generally indicated at 10. The drum is mounted upon a transverse shaft 11, extending across the 25 tank parallel to the beater roll shaft 6 and a short distance behind the beater roll. The shaft 11 is journaled in suitable bearings 12, and at one end is provided with a spur gear 13, designed to mesh with a pinion 14, 30 mounted upon a short shaft 15, stepped in bearings 16 and 17. The shaft 15 carries a pulley 18, connected by a belt 19, with a pulley 20 mounted upon the beater roll shaft 6, adjacent the main drive pulley 22 of the 35 said shaft. The drum 10 comprises two end plates 30, 31, between which extend cross rods 32, upon which grading fingers or members 35 are loosely and hingedly mounted. The fingers 35, formed as shown in detail 40 in Figs. 5 to 8 inclusive, in units, each integrally comprise three fingers 36 spaced apart to form slots 37, the width of the slots being varied, conformable to mesh gauge requirements. The faces of the hubs 45 38, of the finger units, are placed one against the other upon the rod 32, thus forming continuous strainer and grader drum surfaces crosswise or longitudinal of the axis.

In the form shown for a given diameter 50 of drum, eight finger supporting rods 32 are employed, and the fingers are of a length to reach the spacing between the two adjoining rods, pivoting upon the rod and loosely bearing upon the next adjoining rod, upon 55 the upward and forward half cycle of the drum. Thus the upward semi-circumference of the drum provides a screen surface for receiving the pulp conveyed thereupon by the beater roll. On the downward return 60 half cycle of the drum, the fingers freely swing by gravity approximately one-half revolution from their closed screen-forming position to their open suspended cleaning position. The shaft 11, within the 65 confines of the drum, is provided with a

feed or conveyor screw 40, operable in the bottom of a trough 41, loosely hung at one end upon the bearing hub of the drum end plate and immovably held at its opposite end to the wall of the tank 1. The end 70 plate 31, (see Fig. 3), is in the form of a flanged annulus, the flange 31^a thereof forming a bearing for the shafts 32. Upon the outer end of the annulus or end plate 31, is a race-way 42, opposed to and coating 75 with the ball bearings 43, carried by a bearing annulus 44, rigidly attached to the tank wall 1, as at 45. The outer end of the drum is thus rotatively supported, and the structure provides means for delivering the 80 graded pulp at the outside of the hollander.

It will be seen by an inspection of Fig. 2, that the drum 10 is so disposed with respect to the beater roll and back fall, that a stream of stock impelled upwardly by the 85 beater roll, between said roll and the curved surface of the back fall, against the hood 47 and baffle 48, will fall directly against the drum grader and strainer fingers, and that portion of stock which is sufficiently 90 fine will pass between said fingers to the interior of the drum to fall into the trough 41 and be carried outwardly into a suitable receptacle placed beneath the delivery end of the trough.

95 The coarser material is carried forwardly by the revolving drum and allowed to drop therefrom at the descending side. Any particles which may adhere to the fingers or between the finger spacing is cast off when the fingers rock from their closed position to their open position. This action cleanses the fingers in each revolution of the drum, presenting a clean screen mesh, to receive the pulp in the upward and forward half cycle. 100 The material advanced and dropping from the drum, falls into the tub and is conveyed by the flow of the mass into the tub, back to the beater roll for further reducing treatment.

105 In Figs. 9 to 11 inclusive, I have shown a modified form of strainer finger 50, in which the width of the slots is varied by the use of plates 51, of suitable cross dimensions, the plates being fastened by screws 52 to the 110 finger projections 53, integral with the hubs 54. By the use of plates of varying widths, the mesh of the drum may be changed to suit requirements.

115 Inasmuch as the grader and strainer units 120 are rotatively mounted upon the shafts 32, each capable of independent movement, they will, when in pendant positions, slightly oscillate to free themselves from foreign substances, such as sticks, strings, or the like, 125 detrimental to their proper functioning as strainer and grader elements.

Having described my invention, I claim:

1. A rotative pulp grading roll comprising a roll frame and members hingedly 130

mounted upon said frame arranged to swing to peripheral position for providing a foraminous surface for the roll in one-half cycle of the roll and to a vertically suspended position in a second half cycle of the roll.

2. A rotative pulp grading roll comprising a roll frame and finger member pivotally mounted upon said frame in a series longitudinal of the axis of the roll and about the frame, capable of swinging to a roll tangent position for providing a foraminous peripheral roll surface at the upper half of the roll and to a vertically suspended position at the lower half of the roll.

3. A rotative pulp grading roll comprising a roll frame and finger members pivotally mounted upon said frame in a series longitudinal of the axis of the roll and about the frame, capable of swinging to a roll tangent position for providing a foraminous peripheral roll surface at the upper half of the roll and to a vertically suspended position at the lower half of the roll, and a conveyor means disposed longitudinally within said roll.

4. A rotative pulp grading roll comprising opposite end frames, a series of cross rods connecting intermediately with said end frames, and in spaced relation about said frames, a plurality of screen forming fingers pivotally mounted upon one cross rod and adapted to rest upon the next adjacent cross rod in one position and freely vertically

suspended from their rod in a second position.

5. A rotative pulp grading roll comprising a rotative frame structure having a series of rods extending longitudinal with the axis of said frame structure and in a spaced relation circumferentially, arms at one end pivotally mounted upon said rods and on each rod arranged in a series side by side, the opposite ends of the arms on one rod adapted to engage a next adjacent rod in one position and swing to a vertically suspended second position.

6. A rotative pulp grading roll comprising a rotative frame structure having a series of rods extending longitudinal with the axis of said frame structure and in a spaced relation circumferentially, arms at one end pivotally mounted upon said rods and on each rod arranged in a series side by side, the opposite ends of the arms on one rod adapted to engage a next adjacent rod in one position and swing to a vertically suspended second position, a plate fixed to each arm spaced from the corresponding plate of the next adjacent arm on the same axis.

In witness whereof, I hereunto subscribe my name, as attested by the two subscribing witnesses.

CHARLES E. HAWKINS.
